SPHYGMOMANOMETER

Cecil Claud Curtis, Washington, D. C.

Application July 9, 1947, Serial No. 759,792

6 Claims. (Cl. 128—2.05)

1

This invention relates to improvements in sphygmomanometers and has for its object the provision of a simple, inexpensive and handy instrument, adapted to be carried in the pocket of a physician or other user, and through the assistance of which blood pressure may be ascertained in an expeditious manner and without the necessity of attendant more complicated or bulky apparatus customarily employed.

The primary object of the invention is to furnish a device of the character above outlined which, although extremely simple and compact, will possess instrumentalities enabling ready application and operation of the device with assurance of accuracy in result.

The preferred embodiment of the invention embodies a handle or body portion comprising telescoping members nested by a suitable spring, the tension of which may be adjusted, the members having two operative features suitably indexed to denote pressures derived from the force required to distend the spring in forcing the telescopic members apart, the outer end of the device conveniently having means to facilitate the gripping thereof in the hand pull thereof, and the inner end of the device being associated with a band adapted to encircle the wrist of a person and be drawn into compressing relationship to the radial branch of the brachial artery.

It will be appreciated by persons skilled in the art—physicians and nurses—that in finding one's blood pressure the artery will be compressed by a pull on the instrument sufficient to cause the encircling band on the wrist to stop the blood flow, ascertained by the feel of the pulse by a finger of the free hand of the operator of the device.

The preferred embodiment of the invention will be illustrated in the accompanying drawings and the construction and arrangement of the various details will be apparent from the specific description hereinafter contained when read in connection with said drawings.

With a full understanding of the construction it will be seen that in addition to the essentially novel characteristic of the invention, residing in the encircling band associated with the pull and tension instrumentalities, other novel features of construction will appear.

In the drawings:

Figure 1 is a side view of the device in completely closed position.

Figure 2 is a similar view with the parts in extended or operating state.

Figure 3 is a longitudinal sectional view.

2

Figure 4 is a similar sectional view taken on a different line (at right angles to Figure 3).

Figure 5 is a side view of the inner member of the telescoping members.

Figure 6 is a transverse sectional view on the line 6—6 of Figure 4.

Figure 7 is a similar view on the line 7—7 of Figure 4.

Figure 8 is a like view on the line 8—8 of Figure 3.

Figures 9, 10 and 11 are plan views of details.

Figure 12 is a separate illustration of a somewhat modified form of clip.

Referring more specifically to the drawings wherein like reference characters designate the same parts in the several views, 15 and 16 are respectively outer and inner tubular members or barrels adapted to have telescopic relationship, the inner barrel when not in use being nested quite entirely within the outer barrel and there held by a normally contracting coiled spring 17, attached at one end to the tubular member 16 near the outer end of the latter, and at the other end attached to the outer end of the tube or barrel 15. The connections are formed in this manner: The spring 17 has its convolutions in contact or very closely related when not expanded, and in the lower end of this spring a threaded cap 18 is inserted, the threads of which cap substantially conform to the coiling of the spring and being of a substantial length to prevent separation of the cap from the spring, although it may be otherwise fastened, if desired. This cap 18 has a threaded bore 19 through which passes the adjusting screw 20, having a complementary thread 21, the screw passing through an opening 22 through the end cap 23 of the tubular member 15 to the exterior of said cap and having a screw head 24 fitted in and bearing against the said cap whereby on operating the screw the spring 17 may be adjusted in either direction as found expedient, to regulate the spring.

The spring passes freely through the opening 25, in the end of the inner tubular member or barrel 16, and has the upper end 26 thereof passed through and secured in an aperture 27 in a plate portion 28 disposed within the member 16 and held in fixed position therein by a cross pin 29.

30 is the cap or closure for the end of the tubular member 16, the cap being secured in position through the medium of inwardly turned elongated flanges 31 and 32 conforming to and fitting snugly within the curved or cylindrical wall of the member 16 and held therein not only by the

pin 29 heretofore referred to, but also by a similar pin 33 passing through the wall of the member 16, and the flanges 31 and 32, and bridging the space between said flanges to support a rotatable tubular shaft or reel 34, to which latter are secured the ends of a tape or loop 35 constituting a wrist band adapted to encircle the wrist of a patient in compressing the artery thereof, as hereinbefore suggested.

The band or loop 35 may be of suitable material that will not unduly stretch, for instance fine, strong linen or silk tape. The inner ends of the band or loop are fastened to the reel 34 and the opposite sides or portions of the loop are adapted to overlie one another when the same are wound upon the reel 34. The opposite portions of the sides of the loop, when the latter is extended for operation, are respectively guided through slots 36 in the cap 30, and when the device is not in use the outer end of the loop will simply engage and be held over or around the end of the cap in close contact therewith. The edges of the band will, however, project slightly beyond the curved surface of the cap so as to facilitate engagement by the thumb and finger of the user when the band is to be withdrawn and put to its expected service.

A spring 34', housed by the hollow shaft of the reel, is secured at one end to the reel and anchored at its opposite end to the adjacent member 16 of the casing to exert a constant winding tendency on the reel and band sufficient to assist in winding up the band or loop when not in service and to hold the band against loose play or outward displacement save when intended to be manually withdrawn.

To afford better assurance of a firm grip on the device when in use, that is, when the band or tape 35 is around the wrist of a patient, and the handle is to be pulled therefrom against the holding tension of the spring 17, provision is made to prevent a slippage of the hand, the same comprising a pair of pivoted abutments 36', contoured in keeping with the shape of the end of the member 15, and adapted to fold into slots to be flush with the exterior surface thereof, but being readily swung outwardly under engagement of a fingernail with the respective ends 37 of the abutments to contact a stop shoulder 38 on the member 15. A hand in gripping the instrument, and contacting with one or both of these abutments, will be firmly retained in operative association with the instrument. The springs 36a, as shown, constitute practical and efficient means for holding the abutments in closed position when out of service.

39 is a pin extending inwardly from the barrel 15 through a slot 40 in the barrel 16 so that these members 15 and 16 will always be prevented from turning relative to each other and will be maintained in proper condition for registering, as now to be pointed out.

Along the surface of the barrel 16 there is a plurality of stops 41, bearing indicia 42 to represent corresponding degrees of pressure, and with these stops a catch or dog 43 is adapted to automatically engage in successive fashion as the barrel 16 is withdrawn from the barrel 15. The catch or dog is pivoted at 44 and is held down by the end 45 of a spring clip 46 pressing on the end of the dog at one of its ends and on the barrel 15 at its end 47. The spring has a double function, namely, to releasably hold the dog in place, and also to serve as a clip to engage the vest pocket after the fashion of the well-known fountain pen clip.

As the tape or band 35 encircling the wrist is forcibly drawn to collapse the artery and correspondingly stop the flow therethrough, and the indication obtained by the degree of withdrawal 5 of the member 16 from the member 15, the successive stops 41 will be engaged by the dog 43 to prevent the retraction of the member 16 under the influence of the then expanded spring 17. The dog 43 is maintained in engagement with 10 its stop by the overlying end 45 of the spring 46 which is riveted or otherwise secured to the dog, the opposite end 47 of the spring 46, as stated, bearing upon the outside of the barrel or member 15, and the intermediate portion of the 15 spring 46 being normally spaced from said barrel. To release the dog from the stop momentarily engaged thereby and to permit the other projected stops and member 16 to be retracted into the member 15, all that is necessary is for the 20 operator to press his thumb against the spaced intermediate portion of the spring 46, which will cause the outer end thereof to rise and coincidentally elevate the dog 43 away from the immediate stop engaged thereby, and out of the 25 path of returning movement of all other projected stops, so that the spring 17 will completely retract and nest the barrel 16 within the barrel 15.

The reel 34 is provided with a knurled or equivalent rewinding wheel 49, fast with the reel, and arranged whereby to project with its marginal portion through a slot 50 in the member 16, accessible to the thumb of the user for manual operation, when necessary or preferred. The companion or outer member 15 has an open ended slot 51 formed therein to accommodate the projecting marginal portion of this knurled wheel 49 when the tubular members or barrels are closely nested or collapsed to non-operating condition.

At times, where less skillful operators may be using the device, and it is desired to insure contact of the loop or band 35 in the most direct and positive position relative to the artery, it is intended to compress, rather than have the tape or band, constituting said loop, pull against a more rigid or bony part of the wrist, the opposite portions of the band or tape may be passed through narrow frictionally engaging slits 53 of a metallic or equivalent strip or button 54 whereby the button 54 may be slid along the opposite portions of the loop to secure a close fit of the loop around the wrist thereby maintaining the effective or direct pressure portion of the loop in line with the handle portion or body of the instrument. Also, this strip or button 54 may at times be shifted to the extreme outer end of the loop 35 and there utilized to constitute a direct and positive pressure medium, more rigid than the fabric of the loop, for functioning as a presser button or the like, engageable over the artery, found desirable in some instances dependent upon the condition of the artery itself.

In the modified form of dog and clip illustrated in Figure 12, it will be seen that instead of having the dog and spring clip of independent or separate members they are, in this instance, formed of a single piece of spring metal, one end thereof 55, being shaped to constitute the dog and the other end 56 being integral with the same to constitute the clip. In this instance, the clip end 56 is curved or rounded to bear against the barrel. The portion of the device, that is, between the dog and the clip, is bent to constitute an eye or bearing 57 to surround a complementary pivot on the barrel (of the type illustrated in Figure 3) and 70 to be confined between the pivot and barrel. In

this instance, as heretofore, the pressure of the thumb on the space intermediate the eye 57 and the end 56 of the clip will coincidentally raise the dog 55 on its pivot to be temporarily out of the path of movement of the stops with which said dog is intended to engage.

It will be seen that a spring 58 is sleeved upon the adjusting screw 21 to exert a sufficient pressure between the head of the screw 18 and the inner end of the cap 23 for the purpose of further insuring against any tendency of the screw 18 or the screw 21 to loosen or turn, especially when the spring 17 is in its maximum state of contraction.

The mode of operation of this invention is as follows:

On preparing to take the systolic blood pressure of a patient the abutments 36' are first swung to a position at right angles to the body of the instrument, which will cause the respective ends 37 of the abutments to engage the bottom wall or stop 38 of the slots formed in the cap 23, acting to brace and steady these abutments. Having placed the abutments in operative position the tape or loop 35 is withdrawn from the reel 34 and placed around a wrist of the patient, having the inner surface of the outer end of the tape or loop in position to have compressing relationship to the radial branch of the brachial artery. The operator now grasps the instrument in his hand, with the abutments in engagement therewith, while with the first two fingers of his other hand he palpates the radial artery of the patient, the thumb of this hand being placed on the posterior surface of the wrist joint as a brace, when a pull of the hand holding the instrument is exerted on the instrument to cause the tape to compress the radial artery. Applying pressure in this manner until the palpitations of the radial artery can no longer be felt a reading of the degree of systolic pressure can be had on reference to the indicia 42 of the barrel 16, due to the relative movement of barrels 15 and 16. When the instrument is no longer needed the abutments are swung back into the receiving slots and the tape or loop is rewound on the reel 34, by the action of the spring 34'. In the event that the spring fails to rewind the tape as desired, manual means is provided in the form of a knurled wheel 49 by which the reel 34 may be rotated.

While in this specification reference has been made to the ascertainment of the systolic blood pressure, it is to be understood that persons skilled in the art to which the invention relates will instantly appreciate that, in the use of the device disclosed, the same embraces the function of also easily ascertaining diastolic pressure. To that end, all that is necessary is for the user to initially ascertain the high point of blood pressure through the compression of the artery, and then, while the instrument is still held under tension, to permit gradual decompression of the artery by releasing the holding dog and causing the retraction of the member 16 back into the member 15 in a step-by-step manipulation of the dog, until the user (customarily the physician or nurse) appreciates, through auditory or tactile indications, that the instrument has reached the stage of adjustment indicative of the decompression where the diastolic pressure will be registered by the instrument.

From the foregoing disclosures it will be appreciated that changes and alterations may be made in the various parts and arrangements,

particularly illustrated herein, without departing from the spirit of the invention as may be defined in the appended claims, as for instance, in the broad aspect of the invention, a fluid pressure instrumentality might be substituted for the spring as the pull-resisting means.

I claim:

1. In a sphygmomanometer a handle portion having spring resisted movable indicating means, and a flexible loop operatively associated therewith adapted to encircle a wrist over an artery therein whereby to compress the same when pull is exerted on the loop against the force of the spring resisted movable indicating means, in combination with a winding element in the handle for the loop when retracted, having a knurled wheel with an exposed engageable portion for manipulation exteriorly of the handle.
2. In a sphygmomanometer a handle portion having spring resisted movable indicating means, and a flexible loop operatively associated therewith adapted to encircle a wrist over an artery therein whereby to compress the same when pull is exerted on the loop against the force of the spring resisted movable indicating means, in combination with an abutment for a hand engaging the handle and pulling on the loop mounted to project laterally of the handle or to be closed into nested relation with the handle.
3. In a sphygmomanometer a handle portion having spring resisted movable indicating means, and a flexible loop operatively associated therewith adapted to encircle a wrist over an artery therein whereby to compress the same when pull is exerted on the loop against the force of the spring resisted movable indicating means, in combination with abutments for a hand engaging the handle and pulling on the loop mounted to project laterally of the handle or to be closed into nested relation with the handle, and spring means associated with the abutments to maintain them in closed position relative to the handle.
4. In a sphygmomanometer a handle portion having spring resisted movable indicating means, and a flexible loop operatively associated therewith adapted to encircle a wrist over an artery therein whereby to compress the same when pull is exerted on the loop against the force of the spring resisted movable indicating means, the handle comprising telescoping members the inner of which is provided with a series of stops and associated indicia and the other provided with a dog to engage said stops as the members move apart, and a pin and slot engagement between the inner and outer members permitting longitudinal movement thereof but preventing relative rotation of the same so as to keep the stops and dog in aligned operative position.
5. In a sphygmomanometer a handle portion having spring resisted movable indicating means, and a flexible loop operatively associated therewith adapted to encircle a wrist over an artery therein whereby to compress the same when pull is exerted on the loop against the force of the spring resisted movable indicating means, in combination with an abutment for a hand engaging the handle and pulling on the loop mounted to project laterally of the handle or to be closed into nested relation with the handle.
6. In a sphygmomanometer, a hollow handle, a hollow indicator movable in and out of the handle having indicia on its outer surface, an extension spring within the indicator having one end connected to the handle and the other end connected to the indicator, and a flexible tape

of loop form having end portions connected to said movable indicator, said tape being adapted to encircle a wrist over an artery therein whereby to compress the artery and move the indicator relative to the handle when pull is exerted on the handle, in combination therewith of a button having slots therein to receive the end portions of said tape and wherein said button is adapted to slide on said tape to regulate the size of said loop, said button in its extreme outermost position on said tape constituting a presser element for application directly over an artery.

CECIL CLAUD CURTIS.
